ABSTRACT OF THE DISCLOSURE

In the core of a plate-fin heat exchanger a tab made from thin material whose height is nearly equal to the height of the passage is secured at the junction point between adjacent passes and extends into the core between one of the fin channels.

BACKGROUND OF THE INVENTION

A typical plate-fin heat exchanger is disclosed in Patent No. 3,196,942 issued to K. R. Prentiss on July 27, 1965, which illustrates a multi-pass heat exchanger which utilizes a portion of the closure bar extending a short distance into the core as the only means for preventing leakage or short circuiting between adjacent passes. The primary use of the shortpiece closure bar at this point is to form a rigid side face for accommodating the pass header.

It is a well known expedient to prevent short circuiting or leakage between adjacent passes by extending this type of end closure bar to extend through the core and define a barrier between passes. Obviously, by running the pass separator the full length of the core, the fin sheets would have to be cut in sections to follow the path of each pass separator. This not only results in a loss of heat transfer area but additionally, adds to the weight, manufacturing complexity and cost of the heat exchanger. I have found that I can obviate this problem by inserting a bent tab made of very thin material whose height matches the height of the passage in a slot in the short pass separator closure bar piece which may run the full length of the core in the fin channel. The fins may be either straight through or wavy since the tab will be sufficiently flexible to follow the sine waves defined by the fin corrugations.

SUMMARY OF INVENTION

The primary object of this invention is to provide a thin, flexible, metal strip extending in the corrugations of fins of a plate-fin heat exchanger core to define a wall between passes formed therein.

Other features and advantages will be apparent from the specification and claims and from the accompanying drawings which illustrate an embodiment of the invention.

BRIEF DESCRIPTION OF THE DRAWINGS

FIGURE 1 is a view in perspective showing a multi-pass heat exchanger.

FIGURE 2 is an enlarged view in elevation with a fragmentary sectional view, and a view in phantom illustrating the invention.

FIGURE 3 is an enlarged sectional view showing the details of the invention.

DESCRIPTION OF THE PREFERRED EMBODIMENT

Referring now to FIG. 1 which generally shows a heat exchanger indicated by numeral 10 having a core 12, low temperature fluid inlet header 14 and low temperature fluid exit header 16, high temperature inlet fluid header 18, high temperature fluid exit header 20 and turning headers 22 and 24. Suitable piping is connected to each of the headers for conducting fluid into core 12 and dis-

2

charging fluid therefrom. In essence, this multi-pass cross-flow heat exchanger passes flow through a series of passes formed in the core so that hot air passes alternate with cold air passages for obtaining indirect heat transfer.

As is typical in a cross-flow plate-fin heat exchanger, the core is constructed by sandwiching corrugated fins between parallelly spaced plates and alternately orienting adjacent layers so that the corrugations which form open-ended channels are 90° with respect to each other. Closure bars are mounted at the side edges of the fins preventing the escapement of fluid.

As shown in FIG. 2, a typical passage 28 of core 12 is formed by disposing fins 30 between spaced plates 32 and 34. This fin extends to all sides of the core. The edges of the fin are sealed off by closure bar 36. Another closure bar (not shown) is mounted on the other edge of the fin. The fin, being corrugated, defines channels opened on each end that extend across the core. Header 20 communicates with one of these ends for distributing fluid through these channels which communicate with another header on the opposite end of the core.

The next adjacent layer is similarly constructed, however, fin 38 has the corrugation running 90° with respect to fin 30. As noted from FIG. 2, plate 34, the bottom wall of passage 28, forms the top wall of passage 40. A second plate 42 is parallelly spaced from plate 34 defining the other wall of passage 40. Closure bar 44 is mounted adjacent the edge of fin 38.

The other passages are similarly formed and the fins, plates and closure bars are stacked and bonded in any suitable manner such as brazing. A bottom and top plate complete the core.

A short piece of closure bar 46 (one being shown) is inserted at the junction points of adjacent passes formed in the passages as shown in FIG. 1. Obviously, some of the fins are cut away to receive these elements.

In accordance with this invention a tab inserted into the side of element 46 is bent to run parallelly with the channels in that passage. The tab is a flat strip preferably made from thin flexible material and is sufficiently wide to touch the adjacent plates and extends part way or completely through the core. This tab serves as a pass separator to prevent fluid in adjacent passes to intermingle.

Hence, for example, it can be appreciated from the foregoing that fluid admitted into header 18 passes through core 12 and into turning header 22 where it is returned, for the second pass, to the core and passes therethrough to turning header 24 wherein again the fluid is passed through core 12 and discharged into the collection header 20 and out through the pipe attached thereto.

Obviously, the fluid in the passage 28 passes through various sections thereof three times. Pass separators may be mounted between each pass in the passage as desired.

FIGURE 3 more clearly shows the details of the tab (like reference numerals refer to like parts in all the figures). The fin 30 (for example) is cut away sufficiently to receive the short piece closure bar 46 and the bent portion of tab 50. A slot 52 is formed in one side of closure bar 46 to receive the end of tab 50. The other passages are likewise fabricated whereupon the unit is assembled and preferably brazed in any suitable manner. It will be obvious that the tab can be inserted in the end of closure bar member 46 if such is desirable. In either case the tab serves to prevent leakage through the gap formed by the cutaway fin portion.

It should be understood that the invention is not limited to the particular embodiments shown and described herein, but that various changes and modifications may be made without departing from the spirit or scope of this novel concept as defined by the following claims.

I claim:

1. A heat exchanger of the type that has a core including a plurality of stacked parallelly spaced flat plates, corrugated fins defining high and low points sandwiched between the plates terminating at the face of core and defining open-ended channels, the corrugated fins in alternate adjacent layers being oriented 90° relative to the corrugated fins in said adjacent layers,

a header attached to the face of the core for directing the flow of heat transfer medium at least back and forth in at least one of said layers, a member extending part way into said core and having a surface aligning with the face of the core so as to provide a welding surface for the header, a pass separator attached to said member extending into the core so as to provide a barrier between the junction where the flow goes back and forth in said layer, said pass separator being thinner relative to the space between the high and low points of said corrugated fins,

5 said pass separator extending rearwardly from said member and into the spaced defined by adjacent high and low points of said corrugated fins.

2. A heat exchanger as claimed in claim 1 wherein said pass separator includes a flat-like flexible member.

3. A heat exchanger as claimed in claim 2 wherein said flexible member is substantially as high as the space between adjacent flat plates.
